UNITED STATES PATENT OFFICE.

FRANK R. ASHTON, OF ROCHESTER, NEW YORK, ASSIGNOR TO THE RICKER MFG. CO., OF ROCHESTER, NEW YORK, A CORPORATION OF NEW YORK.

CATTLE-STANCHION.

1,250,759.

Specification of Letters Patent. Patented Dec. 18, 1917.

Application filed June 7, 1916. Serial No. 102,297.

To all whom it may concern:

Be it known that I, FRANK R. ASHTON, of Rochester, in the county of Monroe and State of New York, have invented certain new and useful Improvements in Cattle-Stanchions; and I do hereby declare the following to be a full, clear, and exact description of the same, reference being had to the accompanying drawings, forming a part of this specification, and to the reference characters marked thereon.

My invention has for its purpose the improvement of cattle stanchions of the general type that embodies a pair of relatively movable members which, when secured together in locked relation, act to retain the cattle by engaging opposite sides of its neck. In a more specific aspect, the invention is intended to afford a readily constructed and efficient locking instrumentality, and to provide a simple mechanism by which it is possible to hold the relatively movable members rigidly and tightly in their locked relation, and furthermore, to permit of separating the parts by an easy manipulation of the locking mechanism. To these and other ends the invention consists in certain improvements and combinations of parts, all as will be hereinafter more fully described, the novel features being pointed out in the claims at the end of the specification.

In the drawings:

Figure 1 is a side elevation showing my invention in its application to a cattle stanchion, and with the parts in locked position;

Fig. 2 is a similar view, partially broken away, and showing the relatively movable members in separated or unlocked relation, and

Fig. 3 is a plan view of the parts as they appear in Fig. 1.

Similar reference characters throughout the several views indicate the same parts.

The present embodiment of my invention comprises a relatively stationary frame member embodying a vertical portion 1 and a horizontal portion 2 at its upper end, and pivotally associated with said relatively stationary frame member is a relatively movable frame member embodying an upright or vertical portion 3, and a horizontal or right angle portion 4 at its lower end which is pivotally connected with the first frame member at 5. The stanchion is supported in the usual manner in a retaining

frame, not shown, by means of chains 6 and 7 connected to the frame members in the manner shown in Fig. 1 and acting to retain the first mentioned frame member in a relatively stationary position and to permit the movable frame member to be separated therefrom in attaching the stanchion or removing it from about the animal's neck. The frame members may be constructed in any desirable way and are preferably formed of T-iron with wooden protective strips 8 on their inner faces.

It is necessary to provide means for guiding the movable frame member properly to its closed position and also for locking it in such closed position, and with this end in view I employ a retaining bar formed by a pair of angle irons 9 attached rigidly to the upper or horizontal portion of the relatively fixed frame member. The retaining bar extends laterally beyond the frame members of the stanchion and is provided with a locking recess 10 at its outermost end, while 11 designates guides formed at the inner end of the retaining bar, being inclined in opposite directions and forming a means for directing the movable frame member properly to its locked position when closing the stanchion. In order to retain the relatively movable frame members in locked or closed relation I employ a locking arm carried by the movable frame member and extending laterally beyond the frame members when closed for engagement with the locking recess 10 aforementioned. The locking arm referred to is preferably in the form of a rod 12 which is bent upon itself forming a locking portion 13 which engages the recess 10, and having its opposite ends 14 and 15 attached to the vertical portion 3 of the movable frame member at points in spaced relation one above the other. This arrangement of the ends of the rod 12 causes the locking portion 13 to exert a pressure downwardly whereby it is moved into engagement with the locking recess 10 and is there held with such firmness as to effectually obviate accidental displacement. The arrangement of the guides 11, combined with the length and leverage of the retaining bar and the locking arm, serves to exert a very positive locking action on the movable frame member and to hold it rigidly in proper relation. To release the parts it is only necessary to elevate slightly the outer 110

end of the locking arm, that is to say, the locking portion 13, sufficiently to move it out of engagement with the locking recess, after which the weight of the movable frame member can carry it to open position as shown in Fig. 2. Outward movement of the frame member is limited by the eye 16, which serves to carry the chain 6 already referred to, and also to engage the locking portion 13 of the locking arm in the manner shown in Fig. 2. To lock the frame members together when the animal is properly positioned within the stanchion, the movable frame member is pushed inwardly from the position shown in Fig. 2 until the locking arm snaps into the locking recess 10.

I claim as my invention:

1. A cattle stanchion comprising a pair of pivotally connected frame members, one of which has a retaining bar extending laterally beyond the frame members, and a locking arm carried by the other frame member for coöperation with the retaining bar and comprising a rod bent upon itself and having its ends secured to the frame member at points one above the other causing the locking arm to press against the retaining bar.

2. A cattle stanchion comprising a pair of pivotally connected frame members, one of which has a retaining bar extending laterally beyond the frame members and having a locking recess at its outer end, and a locking arm carried by the other frame member having its outer end arranged for coöperation with the locking recess and comprising a rod bent upon itself having its ends secured to the frame member at points one above the other whereby the locking arm is held yieldingly against the retaining bar.

3. A cattle stanchion comprising a relatively stationary frame member and a movable frame member pivotally connected

thereto and having a vertically extending portion movable away from the first named frame member, a retaining bar rigidly attached to the upper end of the first named frame member extending laterally beyond the same, and having a recess at its outer end, and a locking arm carried by said vertical portion of the movable frame member and extending laterally over the retaining bar with its outer end coöoperating with said recess, the locking arm comprising a rod bent upon itself having its ends secured at different points one above the other on the frame member so as to exert a downward pressure on the retaining bar.

4. A cattle stanchion comprising a relatively stationary frame member and a movable frame member pivotally connected thereto, a retaining bar upon the first mentioned member having its inner end forked to receive the movable frame member and provided with a locking recess at its outer end, and a locking arm having its outer end arranged for coöperation with the locking recess and comprising a rod bent upon itself having its ends secured to the movable frame member at points one above the other whereby the locking arm is held yieldingly against the retaining bar.

5. A cattle stanchion comprising a pair of pivotally connected frame members one of which has a retaining bar and the other of which carries a locking arm for coöperation with the retaining bar and comprising a rod bent upon itself and having its ends secured to the frame member at points one above the other causing the locking arm to yieldingly engage the retaining bar.

FRANK R. ASHTON.
